ELECTRIC HEDGE TRIMMER

Charles A. Latimer and Dean H. Freund, Toledo, Ohio, assignors to The American Floor Surfacing Machine Company, Toledo, Ohio, a corporation of Ohio

Application February 20, 1953, Serial No. 23,706

Term of patent 14 years

(Cl. D40—1)

To all whom it may concern:

Be it known that we, Charles A. Latimer and Dean H. Freund, citizens of the United States, and residents of Toledo, in the county of Lucas and State of Ohio, have invented a new, original, and ornamental Design for an Electric Hedge Trimmer, of which the following is a specification, reference being had to the accompanying drawings, forming a part thereof.

In the drawings,

Fig. 1 is a perspective view of an electric hedge trimmer, showing our new design;

Fig. 2 is a top plan view thereof;

Fig. 3 is an elevation of the opposite side of the hedge trimmer from that shown in Fig. 1, and

Figs. 4 and 5 are respectively bottom and rear end views thereof.

The dominant features of the design are shown in full lines.

We claim:

The ornamental design for an electric hedge trimmer, substantially as shown and described.
